CLOSING MACHINE

Samuel S. Jacobs, San Mateo, Calif., assignor to
 American Can Company, New York, N. Y., a corporation of New Jersey

Application January 15, 1942, Serial No. 426,909

6 Claims. (Cl. 113—24)

The present invention relates to a closing machine for sealing containers or cans and has particular reference to fluid actuated devices for shifting a can to be closed into sealing position and for maintaining a predetermined pressure on the can during the sealing operation.

In the canning of certain products, such as whole hams and the like, it has been found desirable to provide cans of various heights so that hams of different weights may be packed into cans of the same diameter or other cross section. The use of cans of different heights makes it difficult to seal covers onto them in the same closing machine since the usual closing machine is made with a can lifter mechanism having a fixed stroke.

The instant invention contemplates overcoming this difficulty by providing a closing machine in which the lifter mechanism is actuated by fluid pressure so that the stroke of the can lifter will be flexible enough to take care of can height variations.

An object, therefore, of the invention is the provision of a can closing or sealing machine wherein the can lifter mechanism is operated by fluid pressure to compensate for can height variations and to maintain a uniform lift pressure on the can during the sealing operation, irrespective of the travel required to bring the can into seaming position, i. e., irrespective of the can height.

Another object is the provision of such a lifter mechanism for a can closing machine wherein a can of any height within the range of the machine may be lifted up to the chuck of the closing head without any adjustment by the operator thereby saving time for closing the cans and increasing production.

Another object is the provision of a lifter mechanism of this character wherein the pressure applied to the can during sealing may be set and maintained at a predetermined pressure which in no way is affected by the height of the can.

Another object is the provision of such a lifter mechanism wherein the pressure is maintained on the can but a slight lifting action is continued at a reduced rate of speed during the sealing operation so that a true spinning action is obtained during the interlocking of flanges on the can parts as required in a double seam.

Numerous other objects and advantages of the invention will be apparent as it is better understood from the following description, which, taken

in connection with the accompanying drawings, discloses a preferred embodiment thereof.

Referring to the drawings:

Figure 1 is a vertical section taken through a can closing machine embodying the instant invention;

Fig. 2 is a horizontal section taken substantially along the line 2—2 in Fig. 1, with parts broken away;

10 Figs. 3, 4 and 5 are fragmentary enlarged sectional views of a clutch mechanism used in the machine, the views being taken substantially along the line 3—3 in Fig. 2 and showing the moving parts of the mechanism in different positions;

15 Fig. 6 is a fragmentary sectional detail taken substantially along the line 6—6 in Fig. 4; and

Figs. 7 and 8 are fragmentary enlarged sectional views of fluid pressure devices used in the 20 machine, the views being taken substantially along the line 7—7 in Fig. 2 and showing the moving parts of the devices in different positions.

As a preferred embodiment of the instant invention the drawings illustrate principal parts of a can closing machine of the character disclosed in United States Patent 2,113,591, issued April 12, 1938, to S. S. Jacobs. In such a machine a can A (Fig. 1) having a cover B loosely applied thereto, is manually placed on a vertically movable lifter pad 21 and the latter is actuated to raise the can and cover into a rotatable closing or sealing head 22, for sealing the cover onto the can.

35 In the instant machine the closing head 22 is a usual can closing head having seaming rollers 23. The head is mounted directly above the lifter pad 21 on a sleeve 25 journaled in a bearing 26 formed in a gear casing 27 carried on top of a frame 28 which constitutes the main frame of the machine.

The closing head 22 is continuously rotated by a pair of differential gears 30, 31, mounted respectively on the head sleeve 25 and on a spindle 45 32 carried within the sleeve and journaled above in a bearing 33 of the casing 27. The gears mesh with and are driven by a pair of cooperating gears 34, 35 which are mounted on a short differential shaft 36 journaled in a pair of spaced bearings 37 formed in the gear casing 27. The shaft 36 also carries a grooved pulley 38 which is driven by a belt 39 which takes over and is driven by a grooved pulley 41 mounted on a rotor shaft 42 of a continuously operating electric motor 43.

The motor is or may be bolted to the gear casing 27.

When a can A and its superimposed cover B are placed upon the lifter pad 21 for closing, the lifter is actuated through a one revolution clutch device which sets the lifter mechanism in motion for one complete can closing cycle. The clutch device includes a constantly rotating clutch gear 47 (Figs. 1, 2, 3, 4 and 5) which is mounted on a clutch shaft 48 journaled in a pair of spaced bearings 49 formed in the gear casing 27. The gear meshes with and is driven by gear teeth 51 formed on the differential gear shaft 36.

The clutch gear 47 is formed with a hub 54 which surrounds a cam hub 55 of a normally stationary lifter operating cam 56 loosely mounted on the clutch shaft 48. The interior face of the clutch hub is formed with a notch 58 (see Fig. 6) which is engageable by a clutch flapper 59 mounted on a pivot pin 61 secured in the cam hub. The flapper is located in a recess 62 in the cam hub and is backed up by a spring barrel 63 disposed in a bore 64 in the cam hub. The spring barrel tends to push the flapper outwardly toward the inner surface of the clutch hub.

The clutch flapper 59 normally is held out of engagement with the notch 58 in the clutch hub by a horizontal clutch lever 66 (Fig. 3). This lever is mounted on a pivot pin 67 having its ends secured in a pair of spaced lugs 68 which extend inwardly from a wall of the gear casing 27. The inner end of the clutch lever is formed with a beveled cam surface 69 which in normal position engages against the outer surface of the flapper 59 and thus holds it in place within its recess 62 against the resistance of the spring barrel 63.

The outer end of the clutch lever extends through an opening 71 in the gear casing. This end of the lever merges into a handle 72 which extends toward the front of the machine where it is readily accessible to the operator placing the cans to be closed into the machine. A compression spring 73 interposed between the bottom surface of the outer end of the clutch lever and the adjacent wall edge of the gear casing normally maintains the lever in a horizontal position.

By pressing down on the clutch handle 72 the inner end of the clutch lever is lifted out of engagement with the flapper 59, as best shown in Fig. 4, and this releases the flapper so that it rides on the inner surface of the clutch hub 54 of the rotating gear 47. When the notch 58 in the hub comes adjacent the flapper the latter snaps into it and thus connects the cam hub 55 with the clutch hub. The lifter cam 56 thus rotates through one revolution with the clutch gear 47 and it is during this one revolution that the lifter pad 21 is raised, the can A and cover B united, and the lifter returned to its normal position for removal of the sealed can. This is the can sealing cycle hereinbefore mentioned.

At the end of the can sealing cycle the clutch flapper 59 is withdrawn from the notch 58 in the clutch gear hub 54 to release the lifter cam 56 from the clutch gear and thus bring the cam to rest. This removal of the flapper is effected by a barrel cam 75 which is formed on the cam hub 55. This barrel cam engages the raised inner end of the clutch lever 66 near the end of the cam cycle and depresses the lever into its normal position, as best shown in Fig. 5.

In this position it is in the path of travel of

the flapper and when the latter comes adjacent and engages the cam surface 69 on the lever it is pushed out of the clutch notch 58. The cam hub immediately ceases rotation and the clutch lever remains in place to hold the flapper away from the clutch notch until the next actuation of the clutch handle 72.

The lifter pad 21, which is actuated by the lifter cam 56, is secured to the upper end of a vertical plunger rod 81 (Fig. 1) carried in a long bearing 82 of a cylinder 83. In the machine shown in the drawings the effective stroke of the pad is approximately three inches and the range of cans which may be closed is from one to fifteen inches. Hence the cylinder is carried in a bearing 84 so that it may be vertically adjusted to bring the pad into an approximate position for the particular height of the cans being closed. After such an adjustment, the cylinder may be locked in position in any suitable manner, as by a locking screw 85 which is threaded into the machine frame 28. The inner end of the screw bears against the cylinder.

Within the cylinder 83, the lower end of the plunger rod 81 is formed with a plunger head 86 which constitutes a piston within the cylinder. The plunger head is backed up by a compression spring 87 disposed around the rod and interposed between the plunger head and the rod bearing 82. The spring forces down on the plunger head and thus normally holds the lifter pad 21 in its lowermost position.

The lifter pad 21 is raised under pressure of a fluid medium, preferably oil, which acts against the bottom surface of the plunger head 86. For this purpose the lower end of the cylinder 83 is fitted with a cap 91 having a port hole 92 which leads from a pipe connection or fitting 93 threaded into the cap. The pipe connection holds one end of a flexible tube 95 which extends up through the machine frame 28. The upper end of the tube projects through a wall of the frame and is connected to a valve plate 97 (see Figs. 7 and 8) of an oil reservoir 98 secured to a side of the gear casing 27. The tube leads from an outlet 101 in the valve plate and this outlet is in communication with a recess 102 in the plate.

The valve plate recess 102 constitutes part of a liquid pump which is built into the reservoir 98 below the level of the oil contained within the reservoir. The pump comprises a piston 105 which slides in a cylinder 106 formed in the reservoir. Ports 107, 108 in the walls of the submerged cylinder permit the oil to flow into the pump cylinder and the tube 95 and keep them filled. The inner end of the piston is formed with a lug 111 which carries a cam roller 112 (Fig. 2) which operates against the lifter cam 56 hereinbefore described. The roller is held against the cam by a compression spring 113 which is disposed between the piston and the valve plate at the recess 102.

Thus when the lifter cam 56 begins to rotate through a can cycle by actuation of the clutch device hereinbefore described, the cam pushes the pump piston 105 outwardly through a forward stroke. As soon as the piston begins to move, it closes the ports 107, 108 in the cylinder walls and thereby traps within the cylinder the oil which flowed into it through the ports. As the piston continues to move forward this trapped oil is forced through the outlet 101 in the valve plate 97 and thence into and through the tube 95 to the lifter cylinder 83. The force of the oil acting against the plunger head 86 in the lifter

cylinder raises the plunger 91 and the lifter pad 21 with its can A and thus lifts the can into the sealing head 22 for the can closing operation hereinbefore described.

During the can sealing operation the can is held clamped against the sealing head 22 by a steady pressure which is maintained on the lifter mechanism. In this manner as the sealing head rollers 23 interfold the flange parts of the can and its cover to form the double seam joint which unites the cover with the can, the can is continually lifted toward the head and takes up any decrease in height of the can resulting from the bending over of the can flange. Thus a true spinning action on the double seam is brought about and this results in a tighter and more hermetic seam than may otherwise be obtained in machines of this character.

This pressure is brought about by the engagement of the can with the seaming head 22 and by the pump piston 105 continuing its forward movement against the oil in the pump cylinder 106 and forcing this oil through a by-pass valve 115 in the valve plate 97. This by-pass valve includes an outlet port 116 formed in the valve plate and in communication with the pump recess 102.

The by-pass outlet port 116 leads into a stationary hollow valve member 117 having a concave seat 118 which normally receives a conical valve head 119 formed on a vertical valve stem 121. The valve member and the valve head and its stem are disposed in a bore 122 in the valve plate.

The upper end of the valve stem 121 slides in a bearing formed in an adjusting screw 125 threaded into the walls of the plate surrounding the bore 122. A compression spring 126 located around the valve stem and interposed between the screw 125 and the valve head 119 holds the latter in its normal closed position against the valve seat 118.

When the rising can A on the lifter pad 21 engages against the sealing head 22, the oil in the pump cylinder 106 under pressure of the moving piston 105 forces the oil up against the by-pass valve head 119 and thus partially opens the valve against the resistance of the spring 126, as best shown in Fig. 8. The oil flows up through the partially open valve and empties into the reservoir 98 by way of a pair of aligned holes 131, 132 formed respectively in the valve plate 97 and in the adjacent wall of the reservoir. By turning the screw 125 the pressure on the spring 126 may be adjusted so that a greater or a lesser force exerted by the oil will be required to open the valve sufficiently to permit the by-passing of the oil.

In this manner the maintained pressure on the lifter pad 21 and the can A may be regulated to any pressure required to effect a proper sealing or uniting of the can and its cover. This pressure is maintained for the greater part of the machine cycle.

During the latter portion of the can cycle, the lifter cam 56 permits the pump spring 113 to move the piston 105 through a return stroke in the cylinder 106. This return movement of the piston relieves the pressure on the oil medium and thus reduces the pressure on the lifter pad 21. When the piston has returned to its normal position, the pressure on the lifter pad has been fully dissipated and the pad thereupon moves down under the pressure of the spring 87 to its original lowered position, taking the sealed can

with it so that the can may be removed from the machine.

When the piston 105 is in this returned position, the ports 107, 108 in the walls of the cylinder 106 are exposed and this permits the oil medium from the reservoir 98 to enter the cylinder and replace the oil that was by-passed through the valve 115 during the can closing operation. This completes the can closing cycle.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a container sealing machine in which containers of different heights to be sealed are moved into sealing engagement with a sealing mechanism by a lifter pad having a plunger disposed in a cylinder and actuated by a liquid pressure medium introduced into said cylinder, the combination of a reservoir for holding said medium, pressure means disposed in communication with said reservoir and said cylinder for applying and maintaining pressure through a predetermined volume of the medium onto the plunger within said cylinder for lifting a container on said lifter pad into sealing engagement with said sealing mechanism and for holding the same in such engagement with a predetermined pressure, said volume of medium being in excess of that required to insure such engagement and pressure irrespective of the height of said container, and means operative by the pressure imparted to said medium by said pressure means

40 for returning to said reservoir excess volume of liquid medium between said pressure means and said plunger, whereby to maintain a uniform lift and holding pressure on the container during the sealing operation.

2. In a container sealing machine in which containers of different heights to be sealed are moved into sealing engagement with a sealing mechanism by a lifter pad having a plunger disposed in a cylinder and actuated by a liquid pressure medium introduced into said cylinder, the combination of a reservoir for holding said medium, means disposed in communication with said cylinder and said reservoir for confining a predetermined volume of the pressure medium introduced thereinto from said reservoir, said predetermined volume being in excess of the volume required to actuate said plunger under a predetermined pressure, means for applying pressure through said confined pressure medium onto the plunger within said cylinder for lifting a container on said lifter pad into sealing engagement with said sealing mechanism to insure such sealing engagement irrespective of the height of said container and to maintain such engagement under a constant pressure, and means operative by the pressure imparted to said medium by said pressure means for returning to said reservoir excess volume of confined liquid medium between said pressure means and said plunger, whereby to compensate for the excess volume of confined pressure medium and to maintain a uniform lift and engaging pressure on the container during the sealing operation.

3. In a container sealing machine in which

containers of different heights to be sealed are moved into sealing engagement with a sealing mechanism by a lifter pad having a plunger disposed in a cylinder and actuated by a liquid pressure medium introduced into said cylinder, the combination of a reservoir for containing the liquid pressure medium, means communicating with said reservoir and with said cylinder for segregating a predetermined volume of the liquid medium, means disposed in said communicating means for applying pressure onto the segregated medium and therethrough onto the plunger in said cylinder for lifting a container on said lifter pad into sealing engagement with said sealing mechanism, said liquid volume being in excess of that required to insure a predetermined constant pressure sealing engagement irrespective of the height of the container, and valve means disposed in communication with the segregated medium and actuated therethrough by said pressure means for by-passing and returning to the reservoir the excess volume of segregated pressure medium, whereby to maintain a uniform lift pressure on the container and to allow for a slight continued lifting action at a reduced rate of speed as the container height is reduced during the sealing operation without exceeding said predetermined pressure.

4. In a container sealing machine in which containers of different heights to be sealed are moved into sealing engagement with a sealing mechanism by a lifter pad having a plunger disposed in a cylinder and actuated by a liquid pressure medium introduced into said cylinder, the combination of a reservoir for containing the liquid pressure medium, means communicating with said reservoir and with said cylinder for segregating a predetermined volume of the liquid medium, a pump disposed in said communicating means for applying pressure onto the segregated medium and therethrough onto the plunger in said cylinder with a predetermined pressure for lifting a container on said lifter pad into sealing engagement with said sealing mechanism and for holding the same under said predetermined pressure, said liquid volume being in excess of that required to insure said sealing engagement and said holding pressure irrespective of the height of the container, and valve controlled means in communication with the segregated medium and actuated therethrough by said pump for by-passing and returning to the reservoir the excess volume of segregated pressure medium, whereby to maintain a uniform lift pressure on the container and to allow for a slight continued lifting action at a reduced rate of speed as the container height is reduced during the sealing operation, and means for regulating said valve means to vary the pressure imparted by said pump to said liquid medium.

5. In a container sealing machine in which containers of different heights to be sealed are moved into sealing engagement with a sealing mechanism by a lifter pad having a plunger dis-

posed in a lifter cylinder and actuated by a liquid pressure medium introduced into said cylinder, the combination of a reservoir for containing the liquid pressure medium, a pump cylinder within said reservoir and disposed below the level of the pressure medium in the reservoir, said pump cylinder having a port connecting the interior of the pump cylinder with the interior of the reservoir so that the liquid pressure medium will flow from the reservoir into the pump cylinder for filling the latter, said pump cylinder further being in communication with said lifter cylinder, a reciprocable piston disposed in said pump cylinder for blocking off said port when the piston moves in one direction to segregate and confine the predetermined volume of pressure medium contained in said pump cylinder and to apply a predetermined amount of pressure onto the segregated medium and therethrough onto the plunger in the lifter cylinder for lifting a container on said lifter pad into sealing engagement with said sealing mechanism and for maintaining said engagement under a constant pressure, said volume of the pressure medium being in excess of that required to insure said engagement irrespective of the height of the container, and valve means disposed in communication with the pump cylinder and actuated by the pressure of the pumped liquid for by-passing and returning to the reservoir the excess confined and segregated liquid medium, whereby to maintain a uniform lift pressure on the container and to allow for a slight continued lifting action at a reduced rate of speed as the container height is reduced during the sealing operation.

6. In a machine for sealing containers of different heights by bringing parts to be sealed into a container sealing mechanism and holding the same under a predetermined pressure within said mechanism during the sealing operation, the combination of a support located beneath the sealing mechanism for receiving a container to be sealed, a pressure cylinder located beneath said support, a piston having movement within said cylinder and connected with said support, a reservoir communicably connected with said cylinder for holding a pressure liquid, a pump disposed in said reservoir for applying pressure to said liquid to actuate said piston therethrough to raise said support and position the container within the sealing mechanism under a predetermined pressure, and valve controlled means communicably connected with said reservoir to maintain a predetermined pressure against said piston to hold the container in the sealing mechanism irrespective of the height of the container and irrespective of the degree of movement of said piston to bring the container into the sealing mechanism, said valve controlled means being actuated by the pressure imparted to said liquid by said pump to return excess liquid to said reservoir, whereby to insure against crushing the container in said sealing mechanism.

SAMUEL S. JACOBS.
